UNITED STATES PATENT OFFICE.

BENJAMIN D. EMANUEL, OF INDIANAPOLIS, INDIANA, ASSIGNOR TO THE ANDERSON TOOL COMPANY, OF ANDERSON, INDIANA, A CORPORATION OF INDIANA.

SCALE.

No. 904,251.

Specification of Letters Patent.

Patented Nov. 17, 1908.

Application filed November 6, 1907. Serial No. 400,939.

To all whom it may concern:

Be it known that I, BENJAMIN D. EMANUEL, of Indianapolis, county of Madison, and State of Indiana, have invented a certain new and useful Scale; and I do hereby declare that the following is a full, clear, and exact description thereof, reference being had to the accompanying drawings, in which like letters refer to like parts.

- 10 The object of this invention is to improve means in scales for maintaining the platform thereon in a truly horizontal position during the vertical movements thereof when the load is deposited thereon and removed.
- 15 Or to state it in another way, my invention causes the horizontal platform in scales to move in a direction that is truly vertical. This object has been accomplished by guides and guide rods and other means below the 20 platform and on a lower level than the platform and lever.

My invention relates to means secured to the platform and extending to a point above the weighing lever at which point it is guided 25 in its vertical movement, said means being entirely free from connection with anything else, whereby it properly accomplishes the object desired.

The full nature of my invention will be 30 understood from the accompanying drawings and the following description and claim:

In the drawings Figure 1 is a central vertical section of a pendulum scale, many 35 parts thereof thus appearing in side elevation. Fig. 2 is the same view of certain parts of what is shown in Fig. 1 in their position when the platform is depressed.

There is shown herein a pendulum scale in 40 which there is a base 10, a casing 11, and a platform 12 riding upon the outer end of a lever 13 fulcrumed between its ends upon the pivot point 14 and carrying a scale beam 15 by means of the cord 16 secured to and 45 operating over the disk 17 tending to draw and hold the indicating bar 18 at zero, said indicating bar being oscillatory on the stand 19 and being actuated by the pendulum weight 20 when relieved by the application 50 of a load on the platform. Above the plat-

form there is a chart 21 containing suitable indicating numerals.

I do not wish my invention to be limited to any particular construction of scales wherein it is desirable to maintain a vertically movable platform in a truly horizontal position.

To the bottom of the platform I rigidly secure the guiding arm 25 above the lever 13 and it extends horizontally into the casing and is turned upward to a vertical position and at its upper end, considerably above the lever 13 and at a level higher than the platform to the link 26 pivotally connected with the bracket 27 secured to the casing 11. It is obvious that this guide bar 25, during the vertical movements of the platform, will maintain it in a horizontal position as the lever is rigidly secured to the platform, and with said platform and guide bar 25 will have a truly vertical movement at all times. This vertical movement is not affected by the arcuate movements of the connecting bar 26, because whatever effect the said movement would have upon the inner end of the guide bar 25 would be offset by a corresponding arcuate movement of the platform in its vertical movement. This results because the length of the connecting bar 26 between its pivots is the same as the distance between the pivots on the lever that supports the platform, and that supports the lever 13 and the portion of the lever 13 between said pivots has the same oscillatory movement as the connecting bar 26.

What I claim as my invention and desire to secure by Letters Patent is:

A computing scale including a casing, a lever pivoted between its ends with one end weighted and projecting into said casing, a lead-receiving platform mounted on the other end of said lever, indicating means, a connection between the indicating means and the weighted end of said lever whereby said lever will control the action of said indicator, a check bar rigidly secured to said platform above said lever and projecting into said casing with its inner end turned upwardly, and a link pivotally connected at one end with the upper end of said check bar

and at its other end with said casing, the length of said link being substantially the same as the distance between the fulcrum of said lever and the fulcrum of said platform, substantially as and for the purpose set forth.

In witness whereof, I have hereunto affixed

my signature in the presence of the witnesses herein named.

BENJAMIN D. EMANUEL.
